UNITED STATES PATENT OFFICE.

HENRY MARTIN AND JOHN HARGREAVES MARTIN, OF BURNLEY, ENGLAND.

MEANS FOR CARRYING OFF IMPURE STEAM OR FUMES ARISING FROM YARN-SIZING APPARATUS, &c.

SPECIFICATION forming part of Letters Patent No. 642,469, dated January 30, 1900.

Application filed April 25, 1899. Serial No. 714,449. (No model.)

To all whom it may concern:

Be it known that we, HENRY MARTIN and JOHN HARGREAVES MARTIN, subjects of the Queen of Great Britain, residing at Burnley, in the county of Lancaster, England, have invented new and useful Improvements in or Relating to Means for Carrying Off Impure Steam or Fumes Arising from Yarn-Sizing Apparatus and other Machinery, of which the following is a specification thereof.

This invention relates especially to what are known as "tape-sizing" machines, but is also applicable to other sizing-machines or to machines wherein a trunk is employed to carry off impure steam or other moisture or fumes arising from materials under treatment, by which a deposit of dirt is caused to be formed or collect on the inner sides of the trunk. It is of frequent occurrence for dirt to accumulate in the trunk to such an extent that any vibration will cause the dirt to be dislodged from said trunk and in the case of a tape-sizing machine cause much damage to the rollers and material. We avoid this by our invention, which we hereinafter describe, reference being made to the accompanying two sheets of drawings, in which—

Figure 1, Sheet 1, is a side view of a portion of the trunk with our invention applied and shown in relative position with the yarn-rollers *g*. Fig. 2 is a sectional view of the front of a portion of the said trunk. On Sheet 2 Fig. 3 is a plan, Fig. 4 an end view, and Fig. 5 a transverse section, of a trough with grid constituting our invention. Fig. 6 is a side view of a part of the trough, showing the application of a modified form of our invention.

In the views similar letters refer to similar parts.

In this invention we fit to the mouth of a trunk, as *a*, (represented in Figs. 1 and 2,) an angular grid, formed by a series of bars, as *b*. The lower ends of the said bars are attached to or rest on or in the hollow of a trough, as *d*. We form the trough *d* of any light non-corrosive sheet metal, with the edges *d'* bent over and wired, and an outlet *d''* at any convenient part for the condensed vapor to pass therefrom. The grid is formed either of wires

or of V-shaped bars that may be produced by 50 pressing or stamping from sheet metal or of bars of other preferred form. The grid *b* may be separate from the trough or may be combined with and united thereto. When the grid is constructed separately from the trough, 55 the ends of the wires or bars forming the grid are united to metallic strips, as *c*, Fig. 3.

In a modification of our invention we form the grid so as to rest on or in one channel only of the trough *d* and rising angularly within 60 the trunk, as shown in Fig. 6. By these means any deposit of dirt that is formed within the trunk and beads of water produced by condensation are conducted into the trough.

In order to obtain access for the purpose of 65 clearing the deposit that may have collected in the troughs or in the grids, we secure the troughs to the trunks by means of strap-hinges, as *e*, or an equivalent.

We prefer to employ grids that are 70 constructed of wires or bars, as hereinbefore described; but other forms of grids may be employed in like manner without departing from our invention.

We claim as our invention—

1. As a means for carrying off impure steam or other moisture or fumes arising from materials under treatment in tape-sizing or like machines, the combination of a trunk having a trough, as at *d*, with an angular grid in the 80 trunk and resting in the channel of the said trough, substantially as described.

2. As a means of carrying off impure steam or other moisture or fumes arising from materials under treatment in tape-sizing or like 85 machines, the combination of a trunk with a trough removably secured to the trunk and a grid applied thereto, substantially as described.

In testimony whereof we have signed our 90 names to this specification in the presence of two subscribing witnesses.

HENRY MARTIN.
JOHN HARGREAVES MARTIN.
